UNITED STATES PATENT OFFICE.

FRANK T. CASPER, OF GATES, NEW YORK, ASSIGNOR TO GENERAL RAILWAY SIGNAL COMPANY, OF GATES, NEW YORK, A CORPORATION OF NEW YORK.

ELECTROMAGNETIC DEVICE.

1,313,878.

Specification of Letters Patent. Patented Aug. 26, 1919.

Application filed April 2, 1917. Serial No. 159,201.

To all whom it may concern:

Be it known that I, FRANK T. CASPER, a citizen of the United States, and resident of the town of Gates, in the county of Monroe and State of New York, have invented a new and useful Electromagnetic Device, of which the following is a specification.

This invention relates to electric interlocking systems in which the functions are 10 operated by alternating current and automatically generate direct current for indication purposes, and has for its principal object the production of a simple and reliable indication magnet which will give the desired operation under the influence of direct 15 current but which will not be affected by alternating current or other periodic fluctuating current.

Other objects and advantages will appear 20 more fully hereafter in the description of the particular embodiment of the invention selected to explain its principles, mode of operation and features of construction; and the novel features of the invention will be 25 pointed out in the appended claims.

In describing the particular embodiments 30 of the invention disclosed herein, reference is made to the accompanying drawings which form part of this specification, in which like reference characters refer to like parts in the several views, and in which:

Figure 1 is a top plan view of an indication magnet embodying this invention; Fig. 2 is a side view, partly in vertical 35 section, of the indication magnet shown in Fig. 1;

Fig. 3 is a simple circuit illustrating the 40 manner in which the indication magnet shown in Figs. 1 and 2 is used in connection with one type of an interlocking system.

Referring to the accompanying drawings, the invention has been shown embodied in an electromagnet especially applicable for use as an indication magnet in electric interlocking systems of the type in which alternating current is used for operating purposes and in which direct current is used for indication purposes; but it is to be clearly understood that electromagnets may be constructed in accordance with this invention in other ways and for use in other connections, as desired. The indication magnet illustrated comprises a yoke 1 to which are fastened two cores 2, the yoke 1 and the cores 2 being made of iron or other magnetic

material according to the well known practice. In the lower end of each core 2 is a screw 3 which serves to fasten a residual washer 4 of brass or other non-magnetic material, and an iron pole piece 5 to the end 60 of the core, said screws 3 being preferably connected by a locking wire 6 which prevents the accidental loosening of these screws after they have once been adjusted. The armature 7 of the indication magnet is 65 guided at its ends by the screws 3, and is connected to the lower end of a plunger 8 which extends upward through a counter-sunk hole 9 in the yoke 1 and terminates in a hardened head 10 which is adapted to operate any 70 suitable form of indication mechanism.

On each core 2 is a winding or coil 11 which is made much shorter than the core 2 and which is held in place thereon by a coil-supporting collar or ring 12 fastened to the 75 corresponding core 2 by a pin 13 or other suitable means. The leads 14 of the coils are preferably disposed in channels formed by grooves in the upper face of a block 15 of fiber or other insulating material and a 80 cover strip of insulating material 16, the block 15 and strip 16 being placed between the upper ends of the coils 11 and the yoke 1. On each core 2 below its corresponding winding or coil 11 is a sleeve or collar 17 85 formed of copper or other suitable electrical non-magnetic conducting material, this sleeve being preferably somewhat shorter than the space between the coil support 12 and the pole piece 5 so as to leave a space 90 between its upper end and said coil support 12.

When direct current is supplied to the windings or coils 11 of the indication magnet shown in Figs. 1 and 2, the armature 7 95 is attracted in the usual way; but when alternating current is supplied to said coils alternating current is induced in the copper sleeves 17 in analogy to the well known transformer action. This current induced 100 in the copper sleeves 17, according to the well known law of induced currents, tends to oppose the alternating flux setting up this induced current, so that the reluctance of the path through the lower portions of 105 the cores 2, the air gaps between said cores and the armature 7, and through the armature 7, is greatly increased, thereby causing a great increase in the leakage of the flux 110 between the coils 11. In other words, the al-

ternating flux set up by the flow of alternating current through the coils 11 is so greatly opposed or choked back by the copper sleeves 17 from passing through the armature 7, 5 that this flux takes the leakage paths directly from core to core without passing through said armature. If found necessary or desirable, the reluctance of the leakage paths may be decreased by making the coil 10 supports 12 of paramagnetic material and decreasing the air gap between them, and in such a construction it is preferable to make the plunger 8 of brass or other non-magnetic material in order that the leakage 15 flux may not have an influence upon this plunger and cause a false operation. In this connection, it has also been found by experiment that it is preferable to have a space between the lower end of each coil or 20 winding 11 and copper sleeve 17, although it is to be understood that the adoption of this expedient depends upon the characteristics and features of the particular design of the electromagnet. Since the copper 25 sleeves 17, which constitute the agency for preventing the operation of the device by alternating current, are solid and substantial members, there is no opportunity for the device to be deranged by the mere breaking 30 or disconnection of wires. For this reason the use of copper sleeves 17, which are in effect a single conducting turn, is preferred, although it is to be understood that a coil of several turns, short circuited on itself, 35 may be used with the same effect and for the same purpose.

From the foregoing it can be seen that there is provided according to this invention a simple and reliable electromagnetic 40 device which is capable of being operated by direct current but which is not affected by alternating current or a similar periodic fluctuating current. The applications and uses of such an electromagnetic device are 45 obviously very numerous in the electrical art, and in Fig. 3 there is illustrated a simple circuit showing how the electromagnetic device embodying this invention may be applied to an alternating current interlocking 50 system. In Fig. 3 there is shown diagrammatically and in accordance with established conventions, a circuit for electric interlocking which in some respects is the same as the circuit used in the well known system of 55 electric interlocking using dynamic indication. Since the construction and operation of the various parts in this system are well known to those skilled in the art and are shown and described in the published art, 60 it is unnecessary to illustrate and describe the construction of these parts in detail. The reference character L designates as a whole the usual lever and its associated contacts. The reference character F designates as a whole the parts associated with

the switch machine or other function, which in general comprises a motor having a field 18 and an armature 19, and a pole changer 20. The motor is of some suitable type which can be operated by alternating current and 70 which is capable of generating dynamically a direct current after each operation of the function. The reference character T designates a transformer which constitutes the source of supply of current used for operating the system; and the letter I indicates the indication magnet constructed as shown in Figs. 1 and 2. The operation of the interlocking system shown in Fig. 3 will be clearly understood by those skilled in the 80 art, especially in connection with the description in the patents hereinbefore mentioned, without further explanation.

The indication magnet, constructed as shown in Figs. 1 and 2, so that it will be 85 operated on direct current but not by alternating current, is especially adapted to this type of interlocking system by reason of the fact that certain derangements of the system, such as crosses between certain 90 wires, and the like, may result in the current from the operating source T being improperly applied to the indication magnet I at a time when the operation of this indication magnet would result in the giving 95 of a false indication. With an indication magnet constructed according to this invention, however, the possibility of such a false indication being given is entirely avoided, and regardless of the way in which alternating current from the operating source T is 100 improperly permitted to flow through the indication magnet I, an operation of the indication magnet cannot be produced under any circumstances, so that an interlocking system including an indication magnet constructed according to this invention is 105 thoroughly safe-guarded against false indication by current derived from the operating source.

Although I have particularly described the construction of one physical embodiment of my invention, and explained the operation and principle thereof; nevertheless, I desire to have it understood that the form 115 selected is merely illustrative, but does not exhaust the possible physical embodiments of the idea of means underlying my invention.

What I claim as new and desire to secure 120 by Letters Patent of the United States, is:

1. In an electric interlocking system, the combination with an electrically operable function having a motor adapted to operate on alternating current and to generate direct 125 current dynamically, of indication mechanism, and an electromagnet for operating said indication mechanism having a short circuited coil which is arranged in inductive relation to each operating winding and 130

which is located between its armature and said operating winding.

2. In an electric interlocking system, the combination with an electrically operable function having a motor adapted to operate on alternating current and to generate direct current dynamically, of indication mechanism, an electromagnetic device for operating said indication mechanism, said 10 electromagnetic device comprising a yoke, cores and a movable armature constituting a magnetic circuit, an operating coil on each core, and a sleeve of electrical conducting material surrounding each core between its 15 operating coil and said armature.

3. In an electric interlocking system, the combination with an electrically operable function having a motor adapted to operate on alternating current and to generate direct 20 current dynamically, of indication mechanism, an electro-magnetic device for operating said indication mechanism comprising a core and a movable armature constituting a magnetic circuit, a winding associated with the core, and a copper sleeve on the core acting upon passage of alternating flux through the core for opposing the passage of flux through the armature, whereby the indication mechanism will be operated 25 by the direct current generated dynamically by the function but will not be operated by the alternation current derived from any improper electrical connection to the source of operating current.

35 4. In an electric interlocking system, the combination with an electrically operable function having a motor adapted to operate on alternating current and to generate direct current dynamically, of indication mechanism comprising an operating winding, a core, a movable armature, and means forming a short circuited conducting path disposed in inductive relation to the operating winding between it and the armature.

45 5. In an electric interlocking system, the combination with an electrically operable function having a motor adapted to operate on alternating current and to generate direct

current dynamically, of an electromagnetic indication device comprising a core and a 50 movable armature constituting a magnetic circuit having leakage paths, an operating winding associated with the core, and protective means arranged in inductive relation to the operating winding and acting to cause 55 a diversion of the flux from the armature to the leakage paths upon the flow of alternating current in the operating winding.

6. In an electric interlocking system, the combination with an electrically operable 60 function having a motor adapted to operate on alternating current and to generate direct current dynamically, of an electromagnetic indication device comprising a core and a 65 movable armature, an operating winding associated with the core, said core extending beyond the ends of said winding, and sleeves of electrical conducting material surrounding the core between the armature and said winding.

7. In an electric interlocking system, the combination with an electrically operable function having a motor adapted to operate on alternating current and to generate direct current dynamically, of an electromagnetic 75 indication device comprising two cores connected by a yoke, an operating winding on each core, said cores extending beyond the ends of the operating windings, a sleeve of electrical conducting material surrounding the extending portion of each core with a space between the sleeve and the winding, and a movable armature associated with the ends of the cores.

8. In an electric interlocking system, the 85 combination with an electrically operable function adapted to be operated by alternating current and employing direct current for indication purposes, of an indication magnet comprising a core and a movable armature 90 constituting a magnetic circuit, an operating winding on the core, and a sleeve of electrical conducting material surrounding the core between the armature and the operating winding.

FRANK T. CASPER.
